INVENTOR.

Lucius L. Battle
By Fitzgerald & Co, Attorneys.

UNITED STATES PATENT OFFICE.

LUCIUS LUCULLUS BATTLE, OF RIVERSIDE, ARKANSAS.

COOLING AND VENTILATING BUILDINGS.

SPECIFICATION forming part of Letters Patent No. 393,137, dated November 20, 1888.

Application filed June 6, 1888. Serial No. 276,207. (No model.)

To all whom it may concern:

Be it known that I, LUCIUS LUCULLUS BATTLE, a citizen of the United States, residing at Riverside, in the county of Woodruff and State of Arkansas, have invented certain new and useful Improvements in Cooling and Ventilating Buildings; and I do hereby declare the following to be a full, clear, and exact description of the invention, such as will enable others skilled in the art to which it appertains to make and use the same.

The invention relates to means for cooling and ventilating dwellings and other buildings; and it consists in the construction and novel arrangement of parts, as hereinafter explained.

The object of the invention is to provide a cheap and simple means of conveying cold air to the several stories of a building, thereby reducing the temperature of the apartments during warm weather.

In the drawings, Figure 1 is a vertical section of the building with my improvement shown in section. Fig. 2 is a detail vertical transverse section of the inlet-ventilator and tank. Fig. 3 is a horizontal section of the shaft on the line $x-x$, Fig. 1. Fig. 4 is a detail vertical section of the tank and troughs.

Referring by letters of reference to the accompanying drawings, A designates the walls of a building; B, a shaft or well, preferably located at one end of the building and extending from the lower floor up through the roof A', as shown, said shaft being divided into three vertical parts, B' B² B³, the middle or inlet ventilator, B², being about three times the size of the outlet-ventilators, B' B³.

a' a² a³ designate the floors of the building.

b b' b² designate openings leading from the rooms near the floors to the inlet-ventilator B², and provided with the vertically-sliding doors e. The opening b is larger than the openings b' b², for the admission of a person to place ice in the bucket, presently explained.

c c' c² show openings near the ceiling of each room opening into the outlet-ventilators B' B³.

C designates a tank mounted on uprights c', a suitable distance above the mouth of the shaft or well, and provided with drains c', opening into troughs D, secured to the bottom of said tank. These troughs are V-shaped in cross-section, and are provided with openings or drains d.

E E E are strips of woolen material secured to the bottoms of the troughs D, and are designed to catch the water coming from the tank C, and also to present several surfaces for evaporating purposes to cool the air in the shaft. These strips extend to the bottom of the ventilator.

Auxiliary troughs G for holding ice are placed in the shaft just below the ventilators b' b², and are designed to be filled with ice to reduce the temperature of the air. These troughs are provided with suitable drain-pipes leading into the pipe I, and a small pipe, i, leading from the bottom of the inlet-ventilator, connects with the pipe I, and acts as a drain for any water that may collect in the bottom of the inlet-ventilator. A water-supply pipe, K, leads up on the inside of the ventilator and discharges into the tank C near the top thereof.

In order to facilitate the supply of refrigerating material to the receptacles a pulley, P, is secured to the under side of the top T of the tank B, and a rope, R, runs over said pulley and carries a bucket or platform for elevating the refrigerating material from the bottom of the well to the several receptacles, as required. It will be seen that the air coming in at the top or opening O is reduced in temperature before it passes out into the rooms below, and will force the warm air out through the ventilators c c' c², as indicated by the arrows on the drawings.

Having described my invention, what I claim, and desire to secure by Letters Patent, is—

The combination, with the walls, floors, and roof of a house, of a shaft having an inlet and two outlet ventilators and having a tank secured to uprights over said ventilators, the troughs D, the woolen strips E, the supply-pipe, the auxiliary troughs placed in the inlet-ventilator below the level of the floors, the drain-pipes, and the sliding doors to regulate the admission of cold air to the apartments, substantially as specified.

In testimony whereof I affix my signature in presence of two witnesses.

LUCIUS LUCULLUS BATTLE.

Witnesses:

S. M. JONES,
R. G. EWING.
